(57) **CLAIM**

(22) Filed: **May 9, 2003**

The ornamental design for a pneumatically operated device for imprinting pictures on balls, as shown and described.

(51) LOC (8) Cl. **18-02**

DESCRIPTION

(52) U.S. Cl. **D18/50**

FIG. 1 is a perspective view of my design for a pneumatically operated device for imprinting pictures on balls according to the present invention;

(58) Field of Search D18/14, 19, 13, D18/23, 15, 99, 50; D15/145; 101/35, 41, 163; 156/DIG. 33, 46, 361, 450, 542, 556

FIG. 2 is a front elevational view thereof;

(56) **References Cited**

FIG. 3 is a right side perspective view thereof;

U.S. PATENT DOCUMENTS

FIG. 4 is a left side perspective view thereof;
